UNITED STATES PATENT OFFICE.

HENRY JAMES CRAYMER, OF PECKHAM, LONDON, ENGLAND.

DECORTICATING FIBROUS MATERIALS.

Application filed June 5, 1924, Serial No. 718,152; and in Great Britain June 29, 1923.

The present invention relates to the decorticating of fibrous materials, and relates more particularly to the separation of the fibers from each other and from the fleshy part of the material by means of a rubbing action transversely to the length of the fibers, caused by feeding the material between rotating rollers which are also moved longitudinally in relatively opposite directions.

Prior to this invention it has only been proposed to produce a to and fro rubbing action on the fibers by means of longitudinally reciprocating rollers, but according to the present invention the fibers are subjected to a continuous rubbing action always in the same direction.

In accordance with the foregoing it is necessary for the fiber containing leaf or other material to be generally fed forward in one direction whilst one surface thereof is simultaneously moved always in the same direction transversely of the direction of feed; and the other surface is simultaneously moved always in the opposite transverse direction. This result may be achieved, according to a further part of the invention, by simultaneously moving the two surfaces always in the same directions equally inclined to opposite sides of the direction of feed, as for instance by passing the material between two surfaces moving generally in the direction of feed but more particularly moving always in the same directions equally and oppositely inclined to such direction of feed.

The invention further includes a machine for carrying the above described process into practical effect. In such machine the material is passed between one or more pairs of rotating rollers which both have line contact at right angles to the direction of feed with the opposite sides of material passing therebetween, said rollers rotating in opposite directions, and their construction being such that when the rollers are rotated every point along the contact line of one roller always moves in the same direction inclined to one side of the direction of feed, and every point along the contact line of the other roller always moves in the same direction inclined to the other side of the direction of feed.

More specifically in the machine herein-

after fully described, rollers of the above kind are divided axially into longitudinally movable sections, and means are provided for moving the sections of each roller successively, first in one direction longitudinally of the roller whilst in contact with the material under treatment and then in the other direction whilst out of contact with the material under treatment, the movements of the sections of the two rollers being so co-related that the roller surfaces in contact with the material under treatment move longitudinally in opposite directions. Thus the material is fed generally in a direction at right angles to the plane of the rollers, but simultaneously its outer surfaces are also, as it were, rubbed always in the same direction transversely across each other. Means may be provided for scraping the surfaces of the rollers to free them from material adhering thereto; and water or other liquid is sprayed on or between the rollers or upon the material after leaving the rollers.

According to a modification the rollers are each constructed of a number of parallel discs placed side by side and co-axially surrounding a common shaft, the discs all being equally inclined angularly to the axis of the shaft and each being rotated in the plane in which it is set. A pair of rollers constituting a set have their shafts disposed parallel and their discs inclined oppositely and equally to the plane containing the two shafts, and are yieldingly pressed towards each other so that when the discs forming the surfaces of the two rollers are rotated they bear with the desired degree of pressure on material fed therebetween.

In order that the invention may be clearly understood, machinery embodying same is hereinafter described by way of example with reference to the accompanying drawings, in which:—

Figure 1 is a plan view of one construction of decorticating machine for carrying the invention into practice,

Figure 2 is an end elevation of the machine,

Figure 3 is a sectional elevation on the line A—A of Figure 1, but to a larger scale and with the front half of the upper roller removed,

Figure 4 is a part sectional and part ele-

100

105

vational side view of a portion of the machine to the same scale as Figure 3, and

Figure 5 is a longitudinal section of a modified construction of roller.

5 Figure 6 is a sectional view elevation of one end thereof showing certain details of the roller.

The machine comprises a plurality of pairs of superposed rollers 1 arranged in a 10 horizontal line in a rectangular frame 2 mounted on longitudinal supporting members 3. The machine is conveniently built up of any desired number of rectangular sections, each carrying a suitable number of 15 pairs of rollers and forming a unit, the several units constituting a complete machine being assembled together, for example, by bolting their frames together. The sides of the frame 2 are built up of horizontal 20 members 9 carrying vertical posts 10 fastened at their upper ends to horizontal bars 11.

The surfaces of the rollers may all be smooth, but preferably, as shown, the first 25 few pairs of rollers are grooved peripherally in order to increase the severity of their action. Such grooves may be parallel to each other and arranged at right angles to, or inclined to the axes of the rollers, or 30 they may be helical. Moreover, the depth, spacing, and/or inclination to the roller axes, of the grooves may be varied throughout the grooved rollers to give a progressively diminishing severity of action as the 35 material passes through the machine.

Between adjacent lower rollers are mounted on brackets transversely of the frame 2, scraper bars 4 which almost touch the roller surfaces which move towards them 40 and serve to remove any fleshy material adhering to the rollers. Said scraper bars 4 are preferably arranged above the level of the roller axes and are wide enough to serve also as bridges and guides for the material 45 between adjacent pairs of rollers. Running longitudinally of the machine above the frame 2 is a water supply pipe 5 having at intervals therealong pipes 6 depending downwardly between adjacent pairs of rollers. On the ends of the pipes 6 are provided transverse pipes 7 which are perforated 50 so as to direct water forwardly and/or backwardly between the rollers for the purpose of washing fleshy matter and juices 55 away from the fibers in their passage through the machine. Water is supplied to the pipe 5 by a pump, tank or other water supplying device.

60 The lower rollers 1 are journaled in stationary bearing blocks 8 fixed in holes in the lower members 9 of the frame 2, and the upper rollers 1 are journaled in bearing blocks 12 slidable between adjacent spaced posts 10 of the frame 2. The bearing blocks 65 12 are suspended from the bars 11 by bolts

13, the upper ends of which pass freely through the bars 11 and carry nuts 14. On the threaded stems of the bolts 13 are hand nuts 15, and springs 16 bear between the nuts 15 and the bars 11. Thus the springs 16 automatically press the upper rollers 1 towards the lower rollers so far as is permitted by the nuts 14. By adjustment of the nuts 14 the spacing of the upper and lower rollers can be regulated, whilst by adjustment of the nuts 15 the pressure of the rollers upon material passing therebetween and of greater thickness than the space between the rollers can be regulated.

The rollers 1 themselves are each divided 80 axially into two longitudinal sections 17 of semi-circular cross section webbed internally at two points to carry polygonal bearing sleeves 18 slidable on the roller shaft 19 which, except at its ends where journaled in the frame 2, is of polygonal section, so that there is rotating driving connection between the roller shaft 19 and the roller sections 17, but the latter are free to slide longitudinally on said shaft. The bearing 85 sleeves 18 are so positioned along the lengths of their roller sections as to allow longitudinal movement of the roller sections 17 as hereinafter described. The shafts 19 are 90 hollow, and lubricating oil is fed into their ends through branches from an oil supply pipe 20, and passes to the surfaces of the shafts through holes formed therein along the paths of the bearing sleeves 18 and within the bearing blocks 8 and 12.

On one side of the machine the upper and lower roller shafts 19 of each pair are geared together by gears 21, and the lower shafts extend sufficiently far to carry bevel gears 22 gearing with a series of bevel wheels 23 along a common shaft 24 extending parallel to the length of the machine and journaled in brackets 25 carried by the supporting members 3. On the opposite side of the machine one of the roller shafts 19 carries a fast driving pulley 26, whereby the machine may be belt driven from a suitable source of power. Obviously, however, fast and loose pulleys could be provided on said shaft, or said shaft may be driven by power in any other suitable and convenient manner.

On the opposite end of each roller section 17 are fastened semi-circular end cams 27, the edges of which contact with fixed horizontally disposed rollers 28 mounted diametrically above and below the shafts 19 on extensions of the bearing blocks 8 and 12. The cam surfaces on each section and on the adjacent ends of the two sections are oppositely inclined so as to cause longitudinal movement of the rollers 1 as they are rotated, as hereinafter described, and on one side of the machine the rollers 28 are arranged below the shafts 19 and on the 125 130

other side they are arranged above the shafts 19. Further, the rollers 1 of each pair are so geared together that co-operating sections 17 of the two rollers move in longitudinally opposite directions.

The ends of the frame 2 are closed by plates 29 having rectangular openings 30 therein through which material can be passed into and out of the machine as the case may be. The side and lower edges of such openings may be flanged at 31 to enable trays, or the like, to be secured in front of said openings if desired. The machine may be conveniently mounted above a trough or well 32 inclined towards a drain, so that the water and the juices and fleshy material separated from the fibers can run to waste.

When in operation the pulley 26 is driven in such a direction that the rollers 1 continually rotate in the appropriate direction, and the raw fiber containing material is fed in through the opening 30 between the peripherally grooved rollers 1 at one end of the machine. The material is carried through the machine and simultaneously crushed by the rollers 1 and at the same time it is subjected to a continuous rubbing action in the same direction transversely to the lengths of the fibers owing to the action of the rollers 28 on the cams 27, the arrangement hereinbefore described being such that in any pair of co-operating rollers, when one operative roller section 17 is moving in one direction transversely of the machine, the other section 17 of the same roller and the co-operating section 17 of the other roller 1 are moving in the opposite transverse direction. Thus, immediately a roller section 17 passes out of contact with the material it is moved transversely in the opposite direction until it again comes in contact with the material when the direction of its transverse motion again changes to the same as it was when previously in contact with the material. Thus in passing through the machine the upper and lower surfaces of the material are always rubbed in the same opposite directions transversely to the lengths of the fibers, the operative, or fiber contacting surfaces of the rollers 1 always having a helical or screwing motion in the same direction which is opposite for the upper and lower sets of rollers.

In the modification illustrated by Figure 5, in place of the rollers 1, I employ decorticating rollers which are built up of a number of metal discs 58 disposed side by side and rotatable on bushes 59 which are bored internally at an angle, preferably of 67½° to their geometrical axes and are keyed to the roller shafts 55. End plates 60 are interposed between the end discs 58 and the worm wheels 57, and any slackness between the discs due to wear is adapted to

be taken up by rotary adjustment of peripheral ring portions 64 on the end rings 58, which ring portions have a screw thread engagement with the central portions of the discs and are provided with holes 74 to enable them to be rotated by a suitable tool. When adjusted the ring portions 64 can be held fast by grub screws 75. The discs 58 of each roller are adapted to be rotated simultaneously by means of longitudinal driving rods 61 which fit into conical recesses in the worm wheels 57 at the ends of the rollers, and pass through registering double conical eccentric bores in the discs 58. The worm wheels 57 are driven by worms common to each co-operating pair of rollers and provided in place of the bevel wheels 23 on a common shaft.

It should be noted that although owing to the rollers being built up of inclined discs 58 their surfaces appear in Figure 5 not to be smooth, yet along the line of contact of co-operating pairs of rollers the surfaces are perfectly smooth, for which reason, if desired, the roller surface may be grooved peripherally, as hereinbefore described for the rollers 1, in order to render the initial decorticating action more severe and to prevent slipping of the material longitudinally of the rollers. Further, although the discs 58 of all the rollers of a machine may have the same inclination to the axis of the roller, the inclinations of the discs 58 in consecutive pairs of rollers may vary in order to give different degrees of severity to the decorticating action.

In regard to Figures 1 to 4 it should be noted that the angles and height of the cams 27 on the rollers 1 may be varied for successive pairs of rollers throughout the machine to alter the severity of action by varying the speed of opposite transverse movement of the roller sections; and various other modifications in the hereinbefore described constructions may be made without departing from the spirit of the invention.

In a machine having a series of pairs of decorticating rollers according to this invention, all the pairs of rollers may rub the fibers in the same direction, i. e. the top surface always in one direction and the bottom surface always in the other direction, or the rubbing action may be in the opposite direction for adjacent pairs of rollers, i. e. each surface of the material is alternately rubbed in opposite directions by consecutive upper or lower rollers. To this end the cams and rollers of the roller sections are so arranged that at any particular moment the operative sections of adjacent upper or lower rollers are moving longitudinally in opposite directions.

What I claim is:

1. A process for decorticating fibrous materials, including the steps of feeding the

- material between a pair of decorticating rollers, and by means of said rollers rubbing the two outer surfaces of the material always in the same contrary directions transversely of the length of the fibers.
2. A method of decorticating fibrous materials, including the step of passing the material between a pair of rollers, the operative surface of one roller being given a motion to feed the material generally forward between the rollers and simultaneously move one surface of the material always in the same direction longitudinally of the roller, and the operative surface of the other roller being given a motion to feed the material generally also in the same direction as the first roller, and to move the other surface of the material always in the same direction longitudinally of the roller, but oppositely to the first roller.
3. A method of decorticating fibrous materials, including the steps of feeding the material between a pair of decorticating rollers, and by means of said rollers simultaneously moving the two surfaces of the material in directions equally inclined to, but on opposite sides of, the common direction of feed.
4. A machine for decorticating fibrous materials, comprising in combination, two co-acting decorticating surfaces, means for moving same continuously in the same feeding direction, and means for moving said surfaces always in the same directions equally but oppositely inclined to the common feeding direction.
5. A machine for decorticating fibrous materials, comprising in combination, a pair of co-acting rollers between which the material is fed, means for rotating each of said rollers in constant opposite directions to give a constant direction of feed, and means for imparting to the material contacting surfaces of said rollers screwing motions always in the same directions for each roller, said directions being opposite for the two rollers.
6. A machine for decorticating fibrous materials, comprising a pair of rotating rollers divided axially into longitudinally movable sections, in combination with means for moving the sections of each roller successively first in one direction longitudinally of the roller whilst in contact with the material under treatment, and then in the other direction whilst out of contact with the material under treatment, said means being so adjusted that the movements of the sections of the two rollers are so co-related that at any given moment the roller surfaces in contact with the material under treatment are moving longitudinally in opposite directions.
7. A machine as set forth in claim 6, including cams on the ends of the roller sections, and rollers journaled on fixed axes, against which rollers said cams bear.
8. A machine as set forth in claim 6, including cams on the ends of the rollers sections, and rollers journaled on fixed axes, against which rollers said cams bear, there being as many fixed rollers as there are roller sections for each roller, and said fixed rollers being disposed equally at opposite ends of the roller sections so as to act on the roller sections successively, the fixed rollers at one end always moving the roller sections of a roller in one direction, and those at the other end always moving the roller sections in the opposite direction.
9. A machine as set forth in claim 6, including parallel shafts for each pair of co-operating rollers, and means for yieldingly pressing said shafts towards each other so that the rollers bear with the desired degree of pressure on material of the normal thickness fed therebetween and yield to material of greater than normal thickness.
10. A machine as set forth in claim 6, comprising a plurality of pairs of decorticating rollers disposed to act on the material successively, a common power shaft for the machine, and means for rotating all of said rollers at equal peripheral speeds from said common power shaft.
11. A machine as set forth in claim 6, comprising a plurality of pairs of decorticating rollers, some of said rollers being grooved peripherally in pairs.
12. A machine for decorticating fibrous materials, comprising a pair of co-operating rollers each divided into sections, means for rotating each of said rollers in constant opposite directions to give a constant direction of feed, and means for imparting relative secondary motion to said sections axially of the rollers during rotation thereof.
13. A machine as set forth in claim 6, including a successively acting series of decorticating rollers, means for rotating all of said rollers to feed material fed therebetween always in the same direction, and means for moving the sections of said rollers axially of the rollers so that at any moment the rollers on each side of the material are all moving alternately in opposite axial directions, co-operating rollers on opposite sides of the material moving also in opposite axial directions.
- In testimony whereof I have signed my name to this specification.

HENRY JAMES CRAYMER.
